UNITED STATES PATENT OFFICE.

CHARLES H. STODDART, OF NEW YORK, N. Y.

WASH-BOILER.

SPECIFICATION forming part of Letters Patent No. 387,605, dated August 7, 1888.

Application filed November 1, 1887. Serial No. 253,948. (Model.)

To all whom it may concern:

Be it known that I, CHARLES H. STODDART, of New York city, New York, have invented certain new and useful Improvements in Fountain Attachments for Wash-Boilers, of which the following is a specification.

My invention relates to that class of portable devices which are designed to be placed in wash-boilers to produce an energetic fountain-like action of the water, which thus circulates among the contained clothes with a cleansing effect. These devices usually consist of a base portion of inverted cup or pan like character which rests upon the bottom of the boiler, and which is provided with an inlet and outlet, a tube rising from the outlet and terminating in an elbow. The cooler water entering the base pan or chamber by means of the inlet therein becomes highly heated in this confined space and, seeking an outlet, rushes up the tube and is forcibly discharged down upon the clothes by means of the elbow.

Various constructions of the base pan or chamber have been heretofore produced, and one species thereof employs a volute or tortuous passage between the inlet and outlet, along which the water rushes in its passage to the discharge-tube. This tortuous passage and its inclosing-chamber have heretofore been constructed in several different ways. In one construction the pan and the tortuous passage were made of cast metal cast integrally in one piece, while in another the parts were also of cast metal cast separately and bolted together. Still another construction employed an inverted cup of sheet metal, the volute or spiral partition being also of sheet metal soldered in place, while a lead weight was attached to the cup to give the device steadiness and hold it in place in the boiler. Now, my invention aims to greatly simplify and cheapen the construction of such fountains; and it consists in the special construction and arrangement of parts, which, briefly, consist in the combination, with the sheet-metal cup or pan, of a cast-metal volute-chamber secured to the pan by bolts or other fastening, thus dispensing with any extraneous weight, and consequently rendering the construction simple, cheap, and durable.

The cast-metal chamber is terminated with a central tubular neck which rises through a

central opening in the pan to receive the fountain tube, while in the side of the pan is cut an opening to admit the water to the volute chamber.

My invention therefore consists in the features here outlined, as hereinafter fully set forth and claimed.

In the annexed drawings, Figure 1 gives a perspective view of my improved fountain, while Fig. 2 is a vertical section thereof, and Fig. 3 an inverted plan.

Referring, therefore, to the drawings, *a* indicates the generating-chamber, which is open at the bottom, as usual, and adapted to be placed on the bottom of the boiler. The interior of the generating-chamber has a volute, spiral, or other tortuous partition, *b*, leading to the center, from which the tube *c* rises, which tube is made in two sections, one sliding on the other, as seen in Fig. 2, to admit of extension or contraction, the upper section, *c'*, being terminated in an elbow to deflect the rising stream of water over the clothes in the usual way. Now, the generating-chamber *a* is made of a common stamped tin or sheet-metal baking-pan inverted and having a circular hole punched centrally out of the bottom and a flap, *d*, cut out of the rim, which is bent inwardly, thus forming a circumferential opening or inlet, *e*, at the rim and a central outlet, *f*, in the bottom of the pan, which becomes the top of the generating-chamber, as seen best in Figs. 2 and 3. The volute or tortuous partition *b* is made of cast metal, preferably cast-iron, which is cast integral with a top plate, *g*, having a central tubular neck, *h*, which snugly fits and rises through the central opening cut in the pan *a*, as best seen in Fig. 2, and receives the tube *c*, while the outer ends of the top plate are secured to the bottom of the pan by two studs, *i*, which pass through both parts and receive nuts on the under side, as seen in Fig. 2, thus securing the cast-iron partition firmly to the sheet-metal pan in a simple and inexpensive manner.

It will be seen in Figs. 1 and 3 that the flap *d*, which is cut out of the rim or side of the pan to form the inlet *e*, is bent inwardly and rests against the circumferential or initial part of the spiral partition *b*, which at its outer end closely approaches the circumference of the pan, while its inner end terminates near the

center of the pan adjacent to the outlet *f*, thus forming a spiral water-passage from the circumferential inlet *e* to the central outlet, *f*, as best seen in Fig. 3.

- 5 It will be seen that the flap *d*, resting tightly on the partition *b* and pressing like a spring flap or valve thereon, covers the joint between the partition and the pan and insures a smoother and more integral inflow of water at the inlet to *e*, and, besides, the spring-flap *d* tends to hold the casting firmly in place, taking up any play in its fastening-screws, and thus prevents looseness or rattle of the parts under the foaming action of the water.
- 15 It may now be appreciated that this construction is not only very simple, strong, and durable, but it dispenses with all soldering in the formation and attachment of the spiral partition with the pan, and as the same is formed 2c of cast-iron, and is hence quite weighty, it thus dispenses with a separate weight and forms

partition and weight in one. This cast partition, being secured to the pan by screws or other fastenings, is much stronger, more durable, and inexpensive than a partition made by 25 soldering, and it thus serves to hold the fountain more steadily in the boiler by reason of its greater weight, and the water-passages in the generating-chamber are at the same time more free and unobstructed by reason of dispensing with the separate weight, so that the action of the fountain is therefore more effective.

What I claim is—

The combination, with the pan *a*, having inlet *e* and flap *d*, of the partition *b*, having plate 35 *g* and neck *h*, with fastening-bolts *i i* and tube *c*, substantially as shown and described.

CHARLES H. STODDART.
